UNITED STATES PATENT OFFICE.

JOHN R. ROSS, OF BOSTON, MASSACHUSETTS.

HAT-PRESS ELEMENT.

1,335,197.

Specification of Letters Patent. Patented Mar. 30, 1920.

Application filed March 5, 1919. Serial No. 280,692.

To all whom it may concern:

Be it known that I, JOHN R. Ross, a citizen of the United States, residing at Boston, in the county of Suffolk and State 5 of Massachusetts, have invented new and useful Improvements in Hat-Press Elements, of which the following is a specification.

This invention relates to a hat press which 10 includes an elliptical crown member which shapes the interior of a hat crown, a fixed elliptical crown-supporting base member on which the crown is removably supported, and a hollow elliptical die member formed 15 to surround the crown member and bear removably on the base member. The base and crown members are rigidly supported by the fixed frame of the press, and are removably secured to the frame, so that different members may be used interchangeably. The die member is detachably secured 20 to a reciprocating frame or carrier movable by the operator on the fixed frame, the arrangement being such that the die member 25 may be depressed by the operator upon the crown member and caused to coöperate with the latter in forming a piece of sheet material, such as buckram, into a hat crown or crown foundation adapted to be covered 30 externally with ornamental fabric.

The invention is embodied in the improvements hereinafter described relating wholly to the base and die members, the object of the improvement being to enable the major 35 axes of these members to be varied in length to conform to crown members of different sizes. Within a certain range of hat sizes the length of the minor axis of the crown does not vary, the variation being in the 40 length of the major axis. In accordance with my invention, I so construct the base member and die member that while their minor axes are practically invariable, their major axes may be varied to a considerable 45 extent.

Of the accompanying drawings forming a part of this specification,—

Figure 1 is a side elevation of a base member and a die member embodying the invention, the top portion of the crown member being shown above the die member, and the base and die members being so adjusted that their major axes are of the minimum length.

Fig. 2 is a view similar to Fig. 1, show-

ing the base and die members adjusted to increase the length of their major axes.

Fig. 3 is a top plan view of the die member.

Fig. 4 is a top plan view of the base 60 member.

Fig. 5 is a section on line 5—5 of Fig. 1, looking downward.

Fig. 6 is a view looking upward from line 6—6 of Fig. 1.

Fig. 7 is a view similar to Fig. 6, showing the two sections of the base member abnormally separated.

Fig. 8 is a section on the plane of line 8—8 of Fig. 2.

The same reference characters indicate the same parts in all of the figures.

In the drawings, 12 represents a crown member of ordinary construction, the member being usually hollow, and having a 75 smooth uninterrupted external surface shaped to conform to any style or shape of hat to be pressed.

13 represents the crown-supporting base member, which may be adapted by any suitable or usual means for attachment to a fixed bed forming a part of the fixed frame of a hat-pressing machine, and is provided with the usual seat 14 (Fig. 8) on which the lower edge of the crown member bears removably, and with the usual seat 15 on which the die member 16 bears removably. The base member and die member are of elliptical form, and each of the three members above referred to coöperates in the 90 usual way with the other members. The die member 16 is detachably secured to a vertically reciprocating frame or carrier guided by the fixed frame of the machine and depressible by the operator through a 95 treadle, until the lower edge of the die member surrounds the base of the crown member 12 and bears on the seat 15, as shown by Figs. 1, 2 and 8. Said carrier and the die member are normally raised by springs with 100 which the machine is provided, and when the die member is raised, sheet material for a hat crown or crown foundation may be placed upon the crown under the die member and caused by the next descent of the 105 die member to conform to the surface of the crown member.

Since my invention relates wholly to the improvements hereinafter described in the base and die members, I do not consider it 110

necessary to illustrate the other parts of the machine of which these members constitute elements, it being sufficient to say that the base member and crown are supported and 5 the die member is supported and reciprocated as usual in machines of this character.

In carrying out my invention, I divide the base member 13 and the die member 16 on lines transverse to their major axes, so

10 that each of said members is composed of two relatively movable sections having opposed separable end faces, each member being provided with means for adjusting its sections to vary the length of its major axis, 15 so that said members may be conformed to interchangeable crown members 12 of different sizes, or, in other words, to either one of a plurality of crown members having major axes of different lengths.

20 As shown by Fig. 4, the base member 13 is divided on a line which is both transverse and oblique to its major axis, so that the base member is composed of two sections, each having opposed separable end faces 13^a. 25 When said faces meet, as shown by Fig. 4, the major axis of the base member is at its minimum length, and when said faces are separated, the length of the major axis is increased, as shown by dotted lines in Figs. 30 4 and 6.

I have here shown as the means for varying the major axis of the base member tapped ears 18, projecting downward from the base member at points adjacent to the 35 end faces 13^a, said ears being grouped in pairs, and the ears of each pair being connected by a right and left threaded screw 19, having a wrench engaging enlargement 20 by which it may be turned. It will be 40 understood, of course, that the internal threads of the ears 18 are formed to coöperate with the right and left threads of the bolt 19.

45 As shown by Fig. 3, the die member 16 is divided on a line which is both transverse and oblique to its major axis, so that the die member is composed of two sections, each having opposed separable end faces 16^a. When said faces meet as shown by Fig. 3, 50 the major axis of the die member is at its minimum length, and when said faces are separated, the length of the major axis is increased, as shown by dotted lines in Figs. 3 and 5.

55 The sections of the die member are provided with outwardly projecting tapped ears 21 adjacent to the end faces 16^a. With said ears are engaged right and left threaded screws 22, each having a nut-engaging enlargement 23. Provision is thus made for varying the length of the major axis of the die member in the same manner that the length of the axis of the base member is varied.

60 When a crown member 12 having a major

axis of minimum length is used, the base and die members are contracted so that their end faces meet as shown by Fig. 1. When a crown member having a major axis of greater length is used, the sections of the 70 base and die members are separated to increase the length of the major axis of said members and conform the same to the length of the major axis of the crown member.

The above-described members may be 75 heated in the usual way by gas or other burner, not shown, placed under the base member, and by burners formed by gas outlets in a gas pipe 24, engaged as shown by Figs. 1 and 2, with the die member, provision being thus made for directing jets of flame against the outer surface of the die member, in accordance with the usual practice.

To bridge the spaces between the sections 85 of the base member 13 and the die member 16, I provide the sections of said members with tongues and grooves, the tongues entering the grooves and providing means for bridging the spaces between the sections 90 when their end faces are separated.

Fig. 7 shows a tongue 26 on one of the sections of the base member, and a groove 27 formed in the other section to receive said tongue. As shown by Figs. 3 and 5, the die 95 member sections are provided with tongues 28 and with grooves 29 arranged to receive said tongues.

It will be understood that in employing the device hereinbefore described the base 100 sections being properly adjusted, a suitable crown is placed thereon and the die member, also properly adjusted to correspond to the crown is raised. A sheet of buckram or other material for forming a hat body is 105 then placed upon the crown and the die depressed to cause it to conform to the exterior smooth surface of the crown. It will be appreciated that it is important to have this exterior surface smooth and unbroken or 110 continuous so that the material will not be ridged or otherwise deformed.

My invention enables the base and die members to be adjusted so that they may conform to as many as five different sizes of 115 crown members. Each size of the hat crown requires the employment of a crown member adapted to that particular size. Heretofore it has been necessary to provide as many base members and die members as there are sizes 120 of crown members. This is rendered unnecessary by my invention, the adjustable base member and the adjustable die member being adapted for use with a number of different sizes of crown members.

125 I claim:

1. A hat press crown support comprising a base member provided with an elliptical crown seat, on which a crown is adapted to bear loosely, said member being divided on 130

a line transverse to the major axis of said seat into two sections having opposed separable end faces and relatively movable to vary the length of the major axis of the 5 crown seat, and means exterior of said member for effecting such adjustment and maintaining the parts in the desired relation, whereby a single base may be employed with either one of a plurality of interchangeable 10 elliptical crowns each of which has a major axis of different length from that of the others.

2. A hat press comprising a base member provided with an elliptical crown seat, on 15 which a crown is adapted to bear loosely, and a correspondingly shaped die seat, said member being divided on a line transverse to the major axes of said seats, means for effecting relative adjustments of the sections 20 of said member to vary the lengths of the major axes of said seats and retain the parts in adjusted position, whereby a single base may be employed with either of a plurality of interchangeable elliptical shaped crowns,

each of which has a major axis of different 25 length from that of the others, and an elliptical shaped die member provided with means for varying the length of its major axis so that it can properly surround any selected crown positioned on the base member. 30

3. A hat press comprising a base member provided with an elliptical crown seat and divided on a line transverse to the major axis of said seat into two sections which are relatively movable to vary the length of said 35 axis, and a plurality of non-adjustable elliptical shaped crowns, each of which has a smooth uninterrupted exterior surface and a major axis of different length from that of the others, said member being provided with 40 means for effecting relative movement of its sections and maintaining the parts in proper relation to provide a seat corresponding to any selected one of said crowns.

In testimony whereof I have affixed my 45 signature.

JOHN R. ROSS.
